CARBON ARC LAMP OPERATION AND ARC
INTENSITY CONTROLJoseph J. Mascuch, Maplewood, and James K.
Elderkin, Montclair, N. J.

Application March 25, 1950, Serial No. 151,834

2 Claims. (Cl. 314—52)

1

This invention relates to carbon arc lamps, and particularly to the control of, and degree of effective illumination obtained from such a lamp.

In the operation of arc lamps, notably arc lamps employed in motion picture film projection work, there is much variation in the effectiveness of the arc under different conditions encountered as the carbon electrodes burn away, and also as between the performance of different individual carbon elements. Moreover, even under the most advantageous conditions, a large part of the illumination supplied by the arc is dissipated before it is directed to the location where it can be most effective as an illuminating instrumentality for the article to be exhibited as, for example, a moving strip of film bearing images to be projected onto a viewing screen.

One major cause of dissipation of illuminating power is lack of complete magnetic control of the arc. As electric energy flows across the gap between negative and positive electrodes, a magnetic field is set up, and the arc burns in a dense ball of flame and gas, concentrated about the electrodes.

As the burning proceeds, the two electrodes become incandescent. The negative electrode tends to round off. The positive electrode produces a flat, slightly concave face, normal to the electrode axis. It is the image of this concave face, heated to white heat, which being placed at the theoretical focal point of an elliptical condensing mirror, produces the white projected light desirable in projection lamps. This burning of the arc, however, without complete external magnetic control, envelopes the positive electrode face in a shroud of partially burned, colored gases, which dissipate the white desirable light emitted from the positive face of crater. As stated above, these gases being highly ionized are subject to magnetic influences.

The present invention has for one of its objects, the correction of the above described dissipating and enshrouding of the inherent magnetic field by novel methods and means. Specifically, the novel method of correction herein disclosed involves the step of introducing a corrective secondary magnetic field of such a magnitude and disposition, in relation to the original magnetic field created by the arc itself, as to create an overpowering magnetic stress that is effective to accelerate the unburned gaseous matter upwards and away from the image crater, in a predefined narrow path, leaving the image crater substantially free of enshrouding, light dissipating gases, thereby making it possible for the maximum in-

2

candescence strength of the image crater to be utilized in projection.

The novel means employed to practice this novel method of control, is herein illustrated as taking the form of an electro-magnet mounted at a distance from the aligned carbon electrodes but having a projecting polar element, or core-piece, of sufficient length to reach almost to the point of arc formation, so that said core can be effective, upon passage of energizing current through the winding surrounding the core, to create the over-powering secondary magnetic stress above described, and thereby direct the gases or flame tail into the desired shape and direction.

Another object of the invention is to provide a novel system of control of the feeding of the positive and negative electrodes toward each other; the novelty including the use of motor-driven reduction gear assemblies individual to each of two feed screws actuating the respective carbon carriers; and independently adjustable electronic timer circuits for controlling motor energization selectively and intermittently, to obtain at each feed screw a rate of advance, per minute of operation, that is exactly correct for the burning characteristics of the carbon rod driven thereby—it being well known that positive and negative carbon rods usually have differing characteristics. Other objects and novel features are pointed out in the following description.

In the accompanying drawing, Fig. 1 shows the invention applied to a pair of aligned carbon electrodes;

Fig. 1a shows an exploded view of one of the clutch assemblies; Figure 1b shows the details of the solenoid.

Figs. 2 and 2A illustrate the tendency of the electrode crater to become enshrouded by light-dissipating gases, in the absence of complete magnetic control.

Figs. 3 and 3A show the appearance of the flame, after its position and shape have been corrected by the use of the present invention.

Fig. 4 shows schematically the electrical connections for control of one of the actuating motors; the said connections being duplicated for the other motor.

Fig. 5 is a schematic wiring diagram.

Referring first to Fig. 1, the apparatus there illustrated includes a pair of carbon electrodes, 10, 11 in alignment, one with the other, and adapted to be fed toward each other by the rotation of two feed screws, each of which is in-

dependently rotated by its own individual driving means illustrated.

Still referring to Fig. 1, the carbons 11 and 10 are shown mounted on the vertical arms, 20 and 21 respectively of carriages 19 and 22 suitably guided in relation to base plate 27. The base plate also carries the two independently operated driving motors, 12 and 13. Extending through the control hubs of carriages 19 and 22 and threadedly engaged with corresponding threads cut internally of said hubs, are feed screws 16, 23, whose ends are rotatably supported in bearings 17, 24 on the base plate 27. The motors rotate the feed screws at greatly reduced speed, in relation to motor speed, by reason of the interposed reduction gear trains 18 and 25 coupled to gears 26, 28 of the feed screw clutch assemblies. This consists of the clutch body 29, leather facing washers 30, backing washer 35, spring washer 36, and nut 37, which can be tightened or loosened to give the proper slipping value to enable the carriages 19 and 22 to be moved back or forward to correctly set the initial arc gap. This is accomplished by means of manually turning the screws by the extending knobs 38, 39.

The rotation of the two feed screws serves to keep the two carbon electrodes moving toward each other at the desired respective rates, as regulated by the respective motor control circuits (only one of which is illustrated in Fig. 4), the objective being to move each electrode forward at a constant rate corresponding exactly to the rate at which its tip is being burned away, and thus maintain a constant width of arc gap between the two electrode tips.

The novel means for obtaining greater intensity of illumination from the crater image is shown in Fig. 1b as including a solenoid 31 having a magnetic core 32 extending horizontally therefrom, and then turning upward to form a vertically disposed extension 33 terminating in a magnetic head 34 disposed immediately adjacent the arc gap, the core 32 being shiftable both longitudinally and rotationally of its axis to secure the desired positioning for most effective arc brilliance (see Figs. 3 and 3A), and then locked in such optimum position.

As previously noted, the magnetic field set up by the arc itself tends to envelope the electrode crater in a wavering shroud of dense gases, dissipating the light emanating from the brilliantly luminescent electrode crater. But the introduction of a correcting magnetic field, as by sending current through the windings of solenoid 31, has the effect of "pointing" the surrounding gases (or "tall flame" as they are called) into a thin vertical cone-like shape (Fig. 3) thus minimizing the shrouding effect and thereby resulting in a clear brilliant white light emanating from the positive crater. By reason of the maximum light efficiency thus attained, the lamp is decidedly

more effective as an illuminating means for picture projection or analogous purposes.

As indicated in Fig. 4 for the control of motor 12, each motor is energized by a circuit having 5 therein a switch 9 oscillating between "make" and "break" positions, as a relay 6 is alternately energized and de-energized; the relay 6 being part of a timer circuit having a single thyratron unit 1 whose grids 3, 4 function in collaboration with resistors R₁—R₅, condensers C₁—C₂, and resistor R₄, to send spaced energy impulses across the tube terminals 2, 5 and thus intermittently energize the relay 6. Supply lines 8 serve as the energy source, both for motor 12, and relay 6.

The resistors R₄ and R₅ are manually adjustable to set the desired frequency rate for the relay 6 and thus control the feeding of electrode 11 or 10 as the case may be. Fig. 5 is a schematic wiring diagram showing an automatic cut off device 30 for automatically interrupting the screw drives when there is no arc current flowing. With the timers 1 and 2 operating, energy impulses are sent through the respective feed motors 13, 12, through relay 30 (see Fig. 4 also) and back to 20 timers completing the circuit. Relay 30, however, will only close when current passes through its coil, that is, only after the arc is struck. Hence, the feed motors are automatically stopped whenever the arc is stopped.

What we claim is:

1. In a carbon arc lamp operating system, a pair of aligned carriages movable toward each other, a positive carbon electrode carried by one of said carriages, a negative carbon electrode carried by the other of said carriages, means including a pair of motors and a pair of gear and clutch assemblies for driving said carriages, said driving means also including a pair of feed screws, each having motion translating engagement with its respective carriage, and means including electronic circuits operating independently of voltage conditions across said electrodes for controlling current flow to each of said motors, to control selectively the feeding rate of each carbon electrode.

2. An operating system as defined in claim 1, including automatic drive interrupting means responsive to arc extinction.

JOSEPH J. MASCUCH,
JAMES K. ELDERKIN.
